UNITED STATES PATENT OFFICE.

CHARLES E. ROWE, OF DAYTON, OHIO.

COLLAR-BUTTON.

1,246,163.

Specification of Letters Patent.

Patented Nov. 13, 1917.

Application filed February 17, 1917. Serial No. 149,350.

To all whom it may concern:

Be it known that I, CHARLES E. ROWE, citizen of the United States, residing at Dayton, in the county of Montgomery and State of Ohio, have invented certain new and useful Improvements in Collar-Buttons; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to new and useful improvements in collar buttons. The object of the invention is to provide a collar button which possesses several advantages not heretofore found in collar buttons. First, my 20 improved collar button has the advantage of serving as a guide or support for holding the front parts of the collar in alinement, that is to say, all of the button holes, to-wit, those in the shirt neckband and those in the 25 collar lie one over the other, thereby preventing one or the other side of the collar from climbing or moving up when the wearer moves his shoulders or neck. Secondly, my improved collar button serves to 30 prevent a collar from buckling up or becoming loosened when the ends of the tie are drawn together through the collar. The collar is prevented from slipping off of the button in drawing the tie.

35 My improved collar button also serves to hold the collar straight. That is to say, the button is of a character that keeps the collar in a horizontal alinement, and any drawing or pulling upon the necktie will not loosen 40 the ends of the collar from the button. Moreover, it is much easier to draw the tie through the collar and thus make a neat tie by the use of my improved collar button. Another advantage due to my improved collar 45 button lies in the fact that it avoids tearing out of the button-holes. This is due to the fact that the collar is easily united and detached from the button without stretching the button-holes unnecessarily. All of these 50 advantages are due to the construction of the shank of the button and the head proper, as will be hereinafter more fully described.

55 Preceding a more detailed description of the invention, reference is made to the accompanying drawings, of which Figure 1 is a front elevation of a collar, the ends of

which are united by means of my improved collar button; Fig. 2 is an enlarged perspective view of the collar button; Fig. 3 is an edge or end elevation thereof; Fig. 4 is a front elevation thereof; Fig. 5 is a side elevation thereof; Fig. 6 is a perspective view showing a slight modification as compared with Fig. 2; and Fig. 7 is another modification as compared with Figs. 2 and 6.

The collar button may be made from a strip of sheet metal, which may be either silver or gold or any of the baser metals or alloys, plated with the more precious metals. As shown in Fig. 2 this strip of metal is bent 70 upon itself to form a base 1, a shank 2, and a head or button portion consisting of lips 3 and 4. The collar button is formed into this shape by suitable dies, and as shown in Fig. 2, the portions of the overlapping strip 75 forming the base 1 are pressed and united firmly together. In Fig. 6 the portions of the strip are not placed in contact in the formation of the button but there is provided an intervening space 5 between the portions of 80 the metal forming the base 1. In other respects the collar button is identically the same as illustrated in Figs. 2 and 6, the same being formed by the use of dies acting upon the metal. The shank 2 is essentially of a 85 broad, flat shape, while the button lips 3 and 4 are rounded to facilitate the ready buttoning and unbuttoning of the collar.

In placing the button in position, the upper lip 3 is first inserted in the button-holes in the shirt neckband and the lower lip 4 is then passed through said button holes. The collar is then buttoned over the upper or longer lip 3 and then slipped over the lower or short lip 4. In removing the 95 collar, the reverse of this operation takes place. The ends of the collar are first slipped over the lower or shorter lip 4 and the said ends of the collar are then slipped from the upper lip 3 of the button. Owing 100 to the shape of the lips 3 and 4 the button-holes are not stretched, and any stiffness of the ends of the collar around the button-holes does not interfere with a ready buttoning or unbuttoning of the collar. Another 105 advantage due to the shape and size of the lips 3 and 4 resides in the fact that the fabric of the collar surrounding the button-holes is preserved and is not broken or torn, as is usually the case with many forms of 110 collar buttons. The front ends of the collar when buttoned lie in alinement. All of the

button-holes, including those in the neck shirt band lie one over the other in alinement. This position is maintained by reason of the broad flat shank 2 which occupies substantially the width of the button-holes. The front of the collar is prevented from being pushed up, and, moreover, the stiffening effect imparted to the front of the collar by the shank 2 enables the collar to be worn with much comfort.

My improved collar button may also be used with equal facility at the back, thereby holding the collar both in the rear and front in a true position around the neck. In Fig. 7 I have shown a slightly modified form of my improved collar button, consisting of a round base 6 and a head 7. In this form of button the same features of advantage reside, for example, the broad, flat shank and the curved upper and lower edges of the insertible end 7 of the button. It is possible to make the button in either way, that is to say, the shank 2 may be made of a solid thickness of metal, or it may be made by bending the metal upon itself and uniting it by solder and finishing it off in the usual way. I wish to lay emphasis on the lips 3 and 4 and their manner of arrangement, one being made shorter than the other. This feature facilitates the attachment or detachment of the collar and renders unnecessary the stretching of the button-holes. These features in connection with the broad, flat shank of the button add to the advantages

by preventing the collar from riding up or out of alinement, all as has been hereinbefore specified. It will be readily seen and understood that the ends of the collar cannot turn when the button-holes are occupied by this broad flat shank, and owing to the further fact that the length of the button-holes is substantially occupied by this flat shank, any undue horizontal movement of the ends of the collar is prevented.

Having described my invention, I claim:

1. A collar button comprising a base portion, a flat broad-faced shank extending from said base portion, and a head united to said shank, said head being of substantially oval form and the greatest diameter of which coincides with the width of the shank, said head having a greater portion of its area on one side of the shank, substantially as specified.

2. As a new article of manufacture, a collar button formed of a single piece of metal bent and united to provide a base portion 1, a broad shank 2, and lips 3 and 4, one of said lips being reduced in size as compared to the other, and both of said lips uniting to form a substantially oval shaped head, substantially as specified.

In testimony whereof I affix my signature, in presence of a witness.

CHAS. E. ROWE.

Witness:

MATTHEW SIEBLER.
